STAPLING MACHINE

William G. Pankonin, Chicago, Ill.

Application June 5, 1950, Serial No. 166,190

37 Claims. (Cl. 1-3)

1

This invention relates to improvements in stapling machines, particularly the so-called "plier-type."

Stapling machines of the plier type are convenient to use and are readily kept in desk drawers and the like when not in use. However, they have been limited to use only by being held in the hand of the operator.

It is an object of this invention, therefore, to provide a stapling machine of the plier type which may also be used as a desk stapler and a tacker.

Another object of the invention is to provide a stapling machine of the plier type which is small, light in weight, neat in appearance, and yet relatively inexpensive to manufacture.

These objects are obtained by providing a stapling machine which has a main housing within which is pivotally mounted a unit consisting of a staple magazine, an injection chute, and a staple driver. A lower handle with an anvil in alignment with such chute is pivoted to the rear of such housing. An upper handle, which is operatively associated with such driver, is pivoted to the front of such housing. The machine may be held by these handles in one hand and operated as a plier type machine. The main housing slidably supports a plunger which is also operatively connected to the staple driver. A lost motion connection between such driver and upper handle permits the plunger to operate without operating such handle. A lost motion lock restrains the lower handle to such movement with respect to the housing as is necessary for clinching staples when the machine is used as a plier or desk type. Upon disengagement of such lock the lower handle may be swung rearwardly and upwardly to expose the bottom of the main housing and ejection chute and the stapling machine may then be used as a tacker. The lower handle has a movable support for desk type operation which may be swung from plier type position (wherein it fits in the fingers of the hand) to desk type position where it supports the machine on a desk or flat surface. When the stapling machine is used as a plier type, the upper and lower handles are both held in the same hand and the squeezing of the hand effects an operation of the stapler. When the stapler is used as a desk type, the plunger is merely pressed downwardly to drive and clinch the staples. In this operation the upper handle is not moved relative to the main housing. When the stapling machine is used as a tacker type, the lost motion lock is disengaged and the lower handle swung out of the way and the staple-driving operation performed by the downward

2

movement of the plunger. The fact that the plunger may be operated without the operation of the upper handle permits the lower handle to be in such out-of-way position.

5 The novel features, which are considered characteristic of the invention, are set forth with particularity in the appended claims. The invention itself, however, both as to its organization and its method of operation, together with additional objects and advantages thereof, will best be understood from the following description of a specific embodiment when read in connection with the accompanying drawings, in which:

Fig. 1 is a view in side elevation of a stapling 10 machine embodying the present invention with the parts positioned for use as a plier type;

Fig. 2 is a top plan view of such stapling machine;

Fig. 3 is a bottom plan view of such stapling 20 machine;

Fig. 4 is a perspective view of such stapling machine showing the arrangement of the parts when the machine is used as a desk type;

Fig. 5 is a perspective view of such machine 25 showing the arrangement of the parts when such stapling machine is used as a tacker;

Fig. 6 is a sectional view taken on line 6-6 of Fig. 1;

Fig. 7 is a sectional view similar to that of 30 Fig. 6 with the parts moved to the position assumed when a staple is driven and clinched while the machine is used as a desk type;

Fig. 8 is a sectional view similar to Fig. 6 with the parts moved to the position assumed when a 35 staple is driven and clinched while the machine is used as a plier type; and

Fig. 9 is a perspective view of the various parts of such stapling machine shown in exploded relation.

PRINCIPAL ELEMENTS

Referring to the drawings by reference numerals, the principal elements of the stapling machine consist of a main housing 10 within which is pivotally mounted at the rear thereof a unit 12 made up of a staple magazine, an ejection chute, and a driver, an upper handle 14 pivotally mounted at the front of said housing, a plunger 16 slidably mounted in the front of said housing, and a lower handle 18 pivoted at the rear of said housing. The staple driver and plunger are maintained in normal raised position by a compression spring 20. The upper handle is maintained in normal raised position by a compression spring 22. The unit 12 is maintained in normal raised posi-

tion within the housing by a compression spring 24. The lower handle is maintained normally spaced from the housing 10 and ejection chute by a riser spring 26. A lost motion lock 28 in the plier or desk type of use prevents the lower handle from swinging out of normal position and permits it to move toward the housing 10 during the clinching of a staple. A desk support 30 movably carried by the lower handle may be swung to desk type position or plier type position.

With the above elements arranged as shown in Fig. 1 the stapling machine is ready for hand operation or plier use. The upper and lower handles fit within the hand of the operator and as they are moved towards each other the ejection chute of unit 12 is forced downwardly from housing 10 until it engages with lower handle 18, as shown in Fig. 8. Continued squeezing drives and clinches a staple. In such use the main housing 10 does not move relative to the lower handle 18.

With the above elements arranged as shown in Fig. 4, the stapling machine is ready for use as a desk type. To operate the machine the plunger 16 is depressed and the housing 10 and the unit 12 simultaneously move toward the handle 18 until the ejection chute contacts such lower handle as shown in Fig. 7. Continued movement of the plunger 16 drives and clinches the staple. In such operation the handle 14 does not move relative to the main housing 10.

With the above elements arranged as shown in Fig. 5, the stapling machine is ready for use as a tacker. As a tacker the machine is operated by depressing the plunger. Since the housing 10 and unit 12 are both resting on the material into which the staple is to be driven, the initial operation of the plunger makes no change in their relationship and a complete depression thereof drives the staple into the material without the clinching of its legs.

Main housing

The main housing 10 has side walls 32 joined by a front wall 34. At the rear of the main housing 10 there are openings 36 for holding the rear pivot 38. Adjacent these openings are slots 40 which function in the tacker position of the device. A pair of slots 42 in the side walls 32 engage lugs 95 on a plate 94 to hold it so that it acts as a base for the spring 24. Near the front the walls 32 have upward projections with slots 44 which engage lugs on the rear guide 46 to hold it in place and let it act as an abutment for the handle 14 limiting its rearward movement. Round openings 48 in such projections receive pins on the ends of the center guide 50 to hold it in place for guiding the plunger 16. A final pair of slots 52 engage lugs on the front guide 54 and secure it so that it also acts as a cover plate for the front portion of the top of housing 10. At the edges of the front wall 34 there are provided a pair of spaced forwardly projecting tabs 56. A slot 58 extends in the front wall between such tabs to provide access to the interior of the housing. These tabs are provided with openings 60 in which the pin 62 is mounted to pivotally mount the lost motion lock 28. Such pin is held in place by a screw 64. Near the top front the walls 32 have aligned openings 66 in which front pivot pin 68 is mounted to pivotally secure the upper handle 14, such pin being held in place by screw 70. A coil spring 72 mounted on the pin 62 has one end engaged in a groove in the back of the lock 28 and the other end inserted through the slot 58 and positioned in front of the forward pivot 68 (see Fig. 6) to continually urge lock 28 into locking position.

Staple, magazine, and driver unit

The unit 12 consists of a magazine, an ejection chute, a magazine follower, a staple-driving blade, and a blade-supporting arm, and functions as a unit upon the operation of the arm to drive staples from the magazine out through the ejection chute. The magazine consists of a core 14 on which staples ride in straddle fashion enclosed by a casing member 76 to provide an ejection chute 78 (see Fig. 6) at the forward end of the magazine. The details of such magazine are shown and described in Patent No. 2,165,572, issued July 11, 1939, to William G. Pankonin. The staple follower mechanism designated 80 is shown and described in Patent No. 2,311,412, issued February 16, 1943, to William G. Pankonin. It is disengageable from the magazine and when inserted as shown in Fig. 6 continually urges the staples toward the ejection chute. A staple-driving blade 82 is mounted on the forward end of a blade-carrying arm 84, the latter being pivoted by pin 86 to upward projections located centrally on the casing. The arm 84 is urged to normal raised position, as shown in Fig. 6, by spring 20. The spring is held on plate 88, which is seated in notches on casing 78, and presses against the under surface of such arm. As previously explained, the spring 24 maintains the unit 12 in normal raised position within the main housing 10 as shown in Fig. 6. The spring 24 reacts between U-shaped bridge 90, the legs of which have dovetail keys 91 which fit in keystone notches 92 in the upper edges of the casing 76 so as to exert an upward force thereon, and a plate 94 which, as previously described, has lugs 95 secured in the notches 42 of the housing. The legs of bridge 90 loosely slide in notches 99 between the lugs 95. The compression of the spring 24 therefore acts to raise the unit 12 upwardly with respect to the housing 10. It is desirable to provide a tubular spacer 96 which is placed on the pin 38 to hold the sides of the casing member properly spaced. It is also desirable to have a fibre pad 97 secured to the rear bottom of the unit 12 so that when the device is used as a tacker (see Fig. 5) such pad may act as a support and hold the stapling machine in upright position.

Upper handle

The upper handle 14 has a hand portion 102 especially designed to fit in the palm of the hand adjacent the base of the thumb. The sides of this portion overlap both the sides of the lower handle 18 and the housing 10. The handle 14 has a front narrow portion 104 the sides of which fit within the side walls 32 and overlap the sides of the blade arm 84. Such sides terminate in spaced ends 106 which straddle the plunger 16 and have openings 108 which receive the front pivot 68 to pivotally mount the handle 14 to the forward end of the housing. The downward movement of the handle 14 is transmitted to the blade arm 84 by means of a loose connection link 110 which is mounted by pivot 112 and spacer 113 to such handle. Elongated notches 114 in the bottom of the link 110 slidably receive pins 116 formed in lateral depressions on the sides of the arm 84. In the normal or at rest position of the stapling machine the pins 116 rest against the tops of the notches 114 (see Fig. 6) to fix the upper position of arm 84 (the handle position

being fixed by its abutment with rear guide 46). When the stapling machine is operated by the plunger 16 the arm 84 will be depressed until it reaches the position shown in Fig. 7 without changing the position of the handle 14 with respect to the housing 10. In such position the pins 116 are substantially at the bottom of the notches 114. The spring 22 acts between the handle 14 and arm 84 to urge the handle 14 to normal or raised position. Such spring is centered and held in the handle 14 by a projection 118 and is centered on the arm 84 by a small lug 120.

Plunger

The plunger 16 has a hollow stem 122, the side walls of which have slots 124 for accommodating the pivoting center guide 50. Such pivoting is necessary to accommodate the slight swinging motion of the plunger as its lower end travels in an arc during the operation of the stapling machine. The plunger terminates in lower tabs 126 which project through slots 128 in the top of lever 84 and are pivoted to such arm by pivot 130 mounted in openings 131 in the side walls thereof. A hand contact cap 132 is secured to the upper end of the plunger for convenience in operating it. Because the plunger is pivoted to the blade arm 84, it will have vertical reciprocal movement even when the stapling machine is operated by the cooperative action of the handles 14 and 18.

Lower handle

The lower handle 18 also functions as a base when the stapling machine is used as a desk type. It has a hand-receiving portion 134 provided with convolutions so that it may be easily held in the fingers of the hand. At its front end 136 it supports an anvil 138 which is constructed and operates substantially the same as that described in Patent No. 2,469,984, issued May 10, 1949, to William G. Pankonin. The lower handle 18 also has a pair of spaced upper arms 140 which slidably overlap the sides of the main housing 10 and are provided with teeth 142 which engage with teeth 143 on the lock 28 to prevent the handle 18 from swinging away from the housing 10 beyond the material-receiving position during the use of the stapling machine as a plier or desk type. During desk use, however, the teeth 143 and 142 will permit the handle 18 to swing into contact with the end of the ejection chute as is shown in Figs. 7 and 8. In such position the teeth 142 and 143 will be spaced and remain in alignment so as to again interengage and limit the swinging apart of the lower handle and main housing. The backs of the teeth are arcuate in shape and in the unconnected position overlap so that when the handle 18 is swung from tacker position (shown in Fig. 5) to desk or plier type position the teeth will automatically snap into overlapping relationship. While it is not necessary, it is desirable to strengthen the arms 140 by forming therein ridges, indicated at 141. The rear of the handle 18 is provided with upwardly projecting wings 144 which straddle the rear end of housing 10. They are provided with openings 146 which receive the rear pivot 38 to swingably mount such arm to the housing at the rear thereof. The wings 141 provide enough clearance between the pivot 38 and the inner bottom of the handle 18 to permit such handle to clear the magazine and staple follower as it swings rearwardly and upwardly of the housing 10 into tacker position (see Fig. 5). In order to hold the

handle 18 in such tacker position the wings 144 have raised locks 148 which snap into frictionally engage the slots 40 when such position is reached. The frictional engagement may be manually overcome to move the handle 18 back to plier or desk type position. When the stapling machine is being used as a plier or desk type, it is necessary to continually urge the handle 18 to its limited downward (outward) position with respect to the housing 10 and this is accomplished by the spring 26 which is mounted in a riser structure 149 which limits the extent of the action of such spring. Such riser structure is substantially identical to that shown and described in Patent No. 2,271,926, issued February 3, 1942, to William G. Pankonin.

Support for desk type operation

The support 30 for desk type operation comprises a channel-like member which is curved longitudinally to substantially conform to the curvature of the hand-holding portion of lower handle 18. It is channel like in cross section and partially overlaps the bottom of the handle 18 to fit snugly thereagainst when in the plier type position as shown in Fig. 1. At its ends the support is provided with flat feet 150 which in the desk type position thereof (see Fig. 4) engage a flat surface at places spaced laterally of the main housing to hold the machine in an upright position. The support is secured to the handle 18 by a headed pin 152 which passes through an opening in the bottom of the lower handle and is secured to the support. A spring 152 encircling said pin reacts between such bottom and the head of such pin to continually urge the support toward the handle. A pair of rounded notches 156 in the central portion of the upper edges of the support 30 engage the curved lower surface of the handle 18 to frictionally hold the support 30 in the desk type position. However, turning pressure exerted manually on the support will break the frictional engagement between such notches and handle and the support 30 may then be swung to the plier type position whence it will also be frictionally held by such spring and pin urging it into engagement with the bottom of the handle.

Operation

In so far as loading the magazine, driving the staple from the ejection chute, and clinching staple legs against the anvil are concerned, the stapling machine herein described operates in substantially the same manner as those described in the aforementioned patents. However, because of the special relationship between the plunger 16, the upper handle 14, and the main housing, the stapling machine may be used as a plier type, a desk type, and a tacker. As previously described, the depression of the plunger 16 will not operate the upper handle 14 and hence the lower handle 18 may be swung upwardly to the tacker position of Fig. 5 and still not interfere with the operation of the machine. The inclusion of the lost motion lock 28 between the main housing 10 and the lower handle 18 produces a novel operation when the device is used as a plier type. As the handle 14 is swung about pivot 68 toward the housing 10 and rear end of lower handle 18, the unit 12 will swing about rear pivot 38 and the bottom of the ejection chute 78 will move away from the housing 10 and rest against the anvil 138 or material thereon. This compresses both springs 24 and 26 to their normal limit, slightly compresses

7
 spring 22 and does not compress spring 20 in a substantial amount. Thereafter continued movement of the handle 14 toward the handle 18 operates the arm 84, compressing spring 20, and driving a staple. However, the squeezing force applied to both handles does not have any effect in forcing the lower handle 18 toward the housing 10. In fact the reverse occurs and the front end of lower handle 18 is urged away from the housing 10. Since such motion is restrained by the lost motion lock 28 a counter-force is set up which reacts against the force applied to each handle and causes a resultant positive drive on the arm 84. In other words, once the unit 12 is in contact with the lower handle 18, the upper handle 14 as one part and the lower handle 18 and housing 10 as the other part act as plier handles about pivot 68 to provide the power to drive and clinch staples. The lock 28, however, permits a quick and easy disconnection of such members so that the machine may be quickly converted for use as a tacker. The other movements of the principal elements during the operation of the machine have been described and such details will not again be repeated. In the application of forces as just described, the housing 10 functions as an arm and will be so termed in the claims.

Although only one embodiment of the invention is shown and described herein, it will be understood that this application is intended to cover such changes or modifications as come within the spirit of the invention or scope of the following claims:

I claim:

1. In a plier type stapler having an operating handle pivotally mounted at one end and provided with an anvil-supporting end, a support for desk operation of said stapler comprising a member the central part of which is pivoted to said handle to permit said member to be swung from plier type position longitudinally of said handle to desk type position transversely of said handle, said member being shaped to rest against said handle when positioned in plier type position to provide a portion easily gripped by the fingers when said stapler is used as a plier type, said member in said desk type position extending to each side of said handle to provide support for and maintain said stapler in an upright position on a flat surface when said stapler is used for desk type operation.

2. In a plier type stapler having an operating handle pivotally mounted at one end and provided with an anvil-supporting end, said handle having a narrow portion adjacent said pivotally mounted end to facilitate the gripping thereof by the fingers of the hand, a support for desk operation of said stapler comprising a member the central part of which is pivoted to said handle to permit said member to be swung from plier type position longitudinally of said handle to desk type position transversely of said handle, said member being shaped to overlie and fit snugly against said narrow portion when positioned in plier type position to provide a portion easily gripped by the fingers when said stapler is used as a plier type, said member in said desk type position extending to each side of said handle to provide support for and maintain said stapler in an upright position on a flat surface when said stapler is used for desk type operation.

3. A plier type stapling machine having a lower operating handle provided with an anvil, said

5 handle having a longitudinally curved portion, a support for desk type operation curved longitudinally to conform with said curved portion and curved laterally to partially overlap said curved portion whereby said support provides a finger-gripping portion when arranged longitudinally of said handle as said machine is used as a plier type, said support having its center pivoted to said curved portion and swingable to a position transversely of said handle to hold said handle on a flat surface when said machine is used as a desk type stapling machine.

4. A plier type stapling machine having a lower operating handle provided with an anvil, said handle having a longitudinally curved portion, a support for desk type operation curved longitudinally to conform with said curved portion and curved laterally to partially overlap said curved portion whereby said support provides a finger-gripping portion when arranged longitudinally of said handle as said machine is used as a plier type, said support having a pair of curved notches cooperable with said curved portion to hold said support in desk type position, said support having its center pivoted to said curved portion and swingable to a position transversely of said handle to hold said handle on a flat surface when said machine is used as a desk type stapling machine.

30 5. A plier type stapling machine having an operating handle provided with an anvil, a support for desk type operation having a pair of spaced feet adapted to rest on a flat surface and support said machine in desk type position, said support having its center pivoted to said handle and swingable from plier type position longitudinally of said handle to desk type position transversely of said handle, and an intermediate portion on said support curved longitudinally to provide a grip for the fingers of the hand of an operator when said support is in plier type position.

45 6. In a plier type stapling machine having an ejection chute from which staples are forcibly discharged and an operating handle carrying an anvil against which staples are clinched as they are driven from said chute, means pivotally mounting said handle so that said anvil has reciprocal movement toward and from said chute to accommodate the reception of material to be 50 stapled between said chute and anvil and the pressing toward each other of said anvil and chute during stapling action and to permit said anvil to be swung from beneath said chute so that staples may be driven therefrom without contacting said anvil, means for constraining said anvil to limited reciprocal movement with respect to said chute and for releasing said anvil for free movement away from said chute beyond said limited reciprocal movement comprising a tooth on said handle directly above and spaced from said anvil, and a spring-biased member 55 swingably associated with said chute and normally biased into overlapping relationship with said tooth to engage said tooth and limit the outward movement of said anvil with respect to said chute, said member being manually swingable out of overlapping relationship with said tooth to permit said anvil to be swung clear of said chute.

60 7. A plier type stapling machine having an operating handle provided with an anvil, main housing, said handle being pivoted at one end to said housing, said anvil being swingable by said handle toward and from said housing in the op-

75

eration of said machine, a pair of arms on said handle in straddle relationship with said housing, a tooth on each arm, a lost motion lock pivoted to said housing and having a pair of teeth one on each side of said housing and interengagable with the teeth on said arms, said teeth being spaced so that when interengaged said anvil will be spaced from said housing an amount sufficient to permit material to be stapled to be inserted therebetween, said teeth unrestric-
ting relative movement of said handle toward said housing from said interengaged position, and a coiled spring having one end engageable with said lock to urge said teeth thereof into locking position.

8. A stapling machine having a unit comprising a staple magazine provided with an ejection chute, a blade-supporting arm pivoted to the magazine, and a staple-driving blade carried by the arm so that reciprocal movement of the arm causes staples to be driven from the ejection chute; a housing for such unit; a manually operable plunger guided by said housing and connected with said blade-supporting arm; a manually operable handle pivoted to said housing; and a link forming a lost motion connection between said handle and said arm to permit said arm to be operated in one direction by said plunger without transmitting motion to said handle.

9. In a plier type stapler, a main housing having a forward end, a staple magazine mounted within said housing and having an ejection chute through which staples are ejected from said magazine, a base associated with said housing and having an anvil in alignment with said chute, staple-driving mechanism for driving staples from said staple magazine one by one against said anvil, a hand-operated plunger reciprocally mounted in said forward end and connected with said mechanism for operating said mechanism, a lever mounted at said forward end for also operating said mechanism, and a loose connection between said lever and said mechanism whereby upon movement of said plunger in a staple-driving direction said lever is inoperative.

10. In a stapling device having staple-driving mechanism, a hand operable plunger mounted for reciprocal movement and connected with said mechanism for operating said mechanism for driving staples from said device, a lever pivotally mounted on said device and cooperable with said mechanism to also drive staples from said device, there being a lost motion connection between said lever and said mechanism, resilient means associated with said mechanism for moving said mechanism and plunger outwardly of said stapling device, and second resilient means operable between said mechanism and said lever to urge said lever outwardly of said stapling device, said second means being operable to hold said lever outwardly of said stapling device when said plunger is used to operate said mechanism.

11. A stapling machine having a housing for mounting a hand-operated stapling plunger, a plunger in said housing having a portion extending therefrom, a hand contact area on said portion whereby plunger is manually depressed, a pivoted handle having a free end for movement to and from said housing, a lever in said housing associated with said plunger, and a one way connection between said handle and said lever whereby movement of said handle in one direction cooperates with said lever to operate said plunger and movement of said handle in an opposite direction does not cause movement of said lever. 75

12. A stapling machine having a housing, a reciprocal stapling plunger mounted in said housing, said plunger projecting above said housing and having a head for hand operation, a handle pivoted to said housing having a free end movable to and from said housing, said handle having an opening through which said plunger projects, and means connecting said plunger and said handle whereby said handle also operates said plunger.

13. In a stapling device having a main housing, a magazine for staples carried by said housing, an arm pivoted on said magazine, a staple-driving tool carried by said arm to drive staples one by one from said staple magazine, a reciprocal manually operable plunger pivotally mounted on said arm and guided by said housing, said plunger and said arm cooperating to drive the staples from said device.

14. In a stapling machine, a housing, a reciprocal stapling plunger mounted in said housing, said plunger having a front wall and a rear wall forming a slot-like opening therebetween, a guide mounted on said housing and fitting in said slot to form one bearing for said plunger, a staple magazine pivoted in said housing, a blade carrying arm movable in said housing and pivotally connected to said magazine and said plunger to guide the lower end thereof, said guide in said slot and said blade carrying arm cooperating to control the movement of said plunger in said housing.

15. A stapling device having a housing, a magazine for staples, staple driving means carried by said housing and said magazine, a base member pivotally mounted to said housing and carrying staple-clinching means, said base member having sides straddling said housing, and disengageable means coacting between said housing and said sides to limit the relative movement between said housing and said base member during a staple-driving operation, said disengageable means being positioned directly above said staple-clinching means.

16. In a hand-operated stapling device having a main housing having a forward end, staple-driving mechanism in said housing including an ejection chute through which staples are ejected at said forward end, a base having a clinching anvil in alignment with said ejection chute against which staple legs are clinched, said base pivoted to said housing, an opening in said base extending rearwardly from said clinching anvil for receiving material to be stapled, and means associated between said housing and said base to limit the relative outward movement of said base to said housing, said means being mounted at the forward end of said opening.

17. In a hand-operated stapling machine, a main housing having a front wall and rearwardly extending sides, a base swingably mounted to said side walls, a lock member pivotally mounted to said housing outside said front wall, and means on said base member in alignment with said lock and engageable with said lock to establish a locked position of said base and prevent relative movement of said base away from said housing, said lock member and said means being disengageable to permit relative movement of said base and said housing from said locked position.

18. In a stapling device having a housing, a magazine for preformed staples carried in and pivoted to said housing and having an ejection chute, a staple-driving tool operable in said chute to drive staples from said magazine, a

11

reciprocal plunger mounted in said housing and connected indirectly with said tool to operate said driving tool, a handle member pivoted on said housing, a lost motion connection between said handle member and said driving tool whereby said tool may be operated by said plunger without operating said handle member, and a base member swingably mounted to said housing, said base member having an anvil against which staples ejected from said chute are clinched when said handle member and said base member are jointly moved toward said housing and when said base member is supported on a flat surface and said plunger depressed toward said base member, said base member being swingable around and away from said chute to permit said device to be usable as a tacker.

19. A plier type stapling machine having oppositely movable handles spaced to be gripped by the hand of an operator for holding said machine and moved toward each other for operating said machine, a plunger for operating said machine having an exposed area adapted to be manually contacted, said plunger being supported adjacent one of said handles and reciprocally movable toward and away from the other of said handles for operating said machine, a support for desk type operation carried by the other of said handles and engageable with a flat surface to hold said machine with said plunger substantially normal to said flat surface, and a lost motion lock for said other of said handles to permit said handle to have limited relative movement with respect to said one of said handles and to be swung away from cooperative relationship therewith.

20. A plier type stapling machine having a main housing provided with a front and rear, a staple magazine and driver unit in said housing, a plunger mounted at said front for operating said unit, an upper handle pivoted to said housing at said front, means providing a lost motion connection between said handle and said unit whereby by said driver unit may be operated by said plunger without moving said upper handle, a lower handle pivoted to said housing at said rear, a lost motion lock operable between said main housing and said lower handle which when locked restrains said lower handle to limited relative movement with respect to said housing, and a support for desk type operation on said lower handle, said support when resting on a flat surface being operable to hold said plunger substantially normal to said surface.

21. A stapling machine having a staple-driving arm, a handle for applying driving force to said arm in one direction of movement of said handle, means for swingably mounting said arm and said handle, means providing an inner and outer limit of travel for each of said arm and handle, a link pivoted to said handle and having an elongated notch in the lower end thereof, and a stub pin on said arm slidable within said notch, said notch being sufficiently long to permit said arm and said handle to be swung relatively in opposite directions to their opposite outer limits while maintaining said pin within said notch.

22. A stapling machine as claimed in claim 21 in which said arm has a lateral depression within which said lower end of said link is slidably received and within which said pin is mounted.

23. A stapling machine as claimed in claim 21 in which said link has a bridge and spaced legs straddling the outside of said arm and the link is pivoted by a pin passing through said legs,

12

there being a spacer on said pin between said legs to maintain said legs spaced from the sides of said arm.

24. In a stapling machine having a housing, a magazine pivoted to said housing, a staple-driving arm pivoted to said magazine, a spring acting between said arm and said magazine to hold said arm in normally raised position, a handle pivoted to said housing and operably associated with said arm to apply operating force thereto when said handle is moved toward said housing, and a spring acting between said arm and said handle to hold said handle in normally raised position, said second spring being located adjacent the pivotal axis of said arm and compressed as said handle is moved toward said arm without said second spring causing said arm to move and compress said first mentioned spring.

25. In a stapling machine having a staple-driving arm provided with a top and sides, an operating plunger for said arm, a slot in said top, a tab on said plunger fitting within said slot, and a pin connecting said tab to said sides below said top.

26. In a stapling machine, a main housing, an elongated magazine within and pivoted to said housing and having an ejection chute, a driving blade operatively mounted in said chute, an arm within said housing pivoted to said magazine and connected to said blade, a first spring reacting between said arm and said magazine to urge said arm upwardly of said magazine, a second spring reacting between said magazine and said housing for urging said magazine upwardly of said housing, a handle pivoted to said housing at the front thereof, said handle having a cooperating connection with said arm whereby downward movement of said handle causes said arm to operate said blade and eject staples from said chute, and a third spring reacting between said arm and said handle to urge said handle to raised position.

27. In a stapling machine, a main housing, an elongated magazine within and pivoted to said housing and having an ejection chute, a driving blade operatively mounted in said chute, an arm within said housing pivoted to said magazine and connected to said blade, a first spring reacting between said arm and said magazine to urge said arm upwardly of said magazine, a second spring reacting between said magazine and said housing for urging said magazine upwardly of said housing, a handle pivoted to said housing at the front thereof, said handle having a cooperating connection with said arm whereby downward movement of said handle causes said arm to operate said blade and eject staples from said chute, and a third spring reacting between said arm and said handle to urge said handle to raised position, said third spring acting on said arm closely adjacent the pivotal axis thereof whereby the force of such spring will not overcome the force of said first spring and cause said arm to move downwardly to transmit force to said magazine without depressing said arm, said second spring acting on said magazine between the pivotal axis of said arm and the pivotal axis of said magazine whereby said spring will be compressed by the force transmitted by said first spring as said first spring is compressed by the downward movement of said handle to cause said magazine to move downwardly of said housing as said handle is moved toward said housing.

28. In a stapling machine, a main housing, an elongated magazine within and pivoted to said

housing and having an ejection chute, a driving blade operatively mounted in said chute, an arm within said housing pivoted to said magazine and connected to said blade, a first spring reacting between said arm and said magazine to urge said arm upwardly of said magazine, a second spring reacting between said magazine and said housing for urging said magazine upwardly of said housing, a handle pivoted to said housing at the front thereof, said handle having a co-operating connection with said arm whereby downward movement of said handle causes said arm to operate said blade and eject staples from said chute, a third spring reacting between said arm and said handle to urge said handle to raised position, a lower handle pivoted to said housing at the rear thereof, and a fourth spring reacting between said lower handle and said magazine for urging said lower handle away from said magazine, said third spring acting on said arm closely adjacent the pivotal axis thereof whereby the force of such spring will not overcome the force of said first spring and cause said arm to move downwardly, said second spring acting on said magazine between the pivotal axis of said arm and the pivotal axis of said magazine whereby said spring will be compressed by the force transmitted by said first spring as said handle is moved toward said lower handle causing said magazine to swing downwardly of said housing and compress both said second and fourth springs until said ejection chute engages said lower handle.

29. In a stapling machine; an elongated magazine having an ejection chute, a staple-driving blade operable in said chute, and a blade support pivoted to said magazine and associated with said blade to operate the same; a first arm pivoted to said magazine at the rear thereof and having an anvil in alinement with said ejection chute when said arm is in staple-clinching position beneath said magazine; a second arm pivoted to said magazine at the rear thereof extending toward the front of said magazine, a third arm pivoted to said second arm at the front thereof and having a driving connection with said blade support, movement of said third arm toward said second arm acting to move said blade support and said magazine as a unit toward said first arm, and means locking said first arm to said second arm so that continued movement of said third arm toward said first arm after said ejection chute has contacted said anvil causes said blade support to move toward said magazine.

30. In a stapling device, a magazine, a staple driver supporting member pivoted to said magazine, an anvil carrying member pivoted to said magazine, an arm pivoted to said magazine, a lock for connecting said anvil carrying member and said arm, and a lever pivoted to said arm and engageable with said supporting member.

31. In a stapling device, a magazine, a staple driver supporting member pivoted to said magazine, a spring for urging said supporting member to raised position, an anvil carrying member pivoted to said magazine, a spring for urging said anvil carrying member away from said magazine, an arm pivoted to said magazine, a spring for urging said arm downwardly of said magazine, a lock for connecting said anvil carrying member and said arm, a lever pivoted to said arm and engageable with said supporting member, and a spring for urging said lever away from said staple supporting member.

32. The combination with a stapling device having a magazine, a staple driver supporting member pivoted to said magazine and an anvil carrying member pivoted to said magazine, an arm pivoted to said magazine and biased downwardly of said magazine, an operating handle pivoted to said arm and connected with said staple driver supporting member to operate the same, and means for temporarily restraining movement of said anvil carrying member away from said arm as said handle is operated.

33. The combination with a stapling device having a magazine, a staple driver supporting member pivoted to said magazine and an anvil carrying member pivoted to said magazine, an arm pivoted to said magazine and biased downwardly of said magazine, an operating handle pivoted to said arm and connected with said staple driver supporting member to operate the same, means for temporarily restraining movement of said anvil carrying member away from said arm as said handle is operated, and a plunger secured to said staple driver and slidably guided in said arm.

34. The combination with a stapling device having a magazine, a staple driver supporting member pivoted to said magazine and an anvil carrying member pivoted to said magazine, an arm pivoted to said magazine and biased downwardly of said magazine, an operating handle pivoted to said arm and connected with said staple driver supporting member to operate the same, means for temporarily restraining movement of said anvil carrying member away from said arm as said handle is operated, a pivoted guide on said arm, and a plunger pivotally secured to said staple driver and movably controlled by said guide.

35. The combination with a stapling device having a magazine, a staple driver supporting member pivoted to said magazine and an anvil carrying member pivoted to said magazine, an arm pivoted to said magazine and biased downwardly of said magazine, and operating handle pivoted to said arm and connected with said staple driver supporting member to operate the same, a tooth on said anvil carrying member, and a tooth on said arm, one of said teeth being spring-biased into locking alignment with the other of said teeth.

36. The combination with a stapling device having a magazine, a staple driver supporting member pivoted to said magazine and an anvil carrying member pivoted to said magazine, an arm pivoted to said magazine and biased downwardly of said magazine, said arm being in the shape of a housing having front and side walls encasing said magazine, an operating handle pivoted to said arm and connected with said staple driver supporting member to operate the same, and means for temporarily restraining the movement of said anvil carrying member away from said arm as said handle is operated.

37. In a stapling machine, a housing, an anvil supporting member pivoted to said housing, a member pivoted at the front of said housing and having teeth positioned on opposite sides of said housing and resiliently biased toward the rear of said housing, and teeth on said anvil supporting member in alignment with said first named teeth.

WILLIAM G. PANKONIN.
